UNITED STATES PATENT OFFICE

2,441,617

STEP CONSTRUCTION

Louis B. Clark, Beaumont, Tex.

Application June 1, 1945, Serial No. 597,005

1 Claim. (Cl. 72—96)

1

This invention relates to step construction.

An object of the invention is to provide a construction of the character described formed of concrete and whose adjacent parts are interlocked together in a novel manner so that the parts can be separately cast and then quickly assembled and interlocked together in the process of erection.

A further object of the invention is to provide a novel type of concrete steps whose separate parts are precast and which may be quickly assembled, in the process of erection, and which, when erected, will be firmly locked together.

With the above and other objects in view the invention has particular relation to certain novel features of construction, arrangement of parts and use, an example of which is given in this specification and illustrated in the accompanying drawings, wherein:

Figure 1 is a fragmentary perspective view partly in section.

Figure 2 is a perspective view of the buttress and step jack.

Figure 3 is a fragmentary end view of the tread and riser.

Figure 4 is an enlarged, cross sectional view taken on the line 4—4 of Figure 3; and

Figure 5 is a fragmentary, cross sectional view taken on the line 5—5 of Figure 1.

In the drawings the numerals 1 designate the foundation piers of the floor which support the concrete floor joist 2 which are spaced the required distance apart. The floor is formed of the concrete slabs 3, hereinafter more specifically described, and the floor is surrounded by the concrete, finishing beams 4.

The numerals 5, 5 designate the step buttresses which are supported on a slab 6 and whose inner ends abut the flooring, as shown in Figure 1.

Secured to, or formed integrally with, the inside of each buttress there is the step jack 7.

Each step and riser is cast in a single unit 8, the riser of the lower step resting on the slab 6 and the riser of each succeeding step resting on the preceding step, from below upwardly, as shown in Figure 1. The rear margin of each step and riser unit has a depending rib 9 extending from end to end thereof. Each riser, and rib, may have a reinforcing rod 10 embedded therein, as more accurately shown in Figure 3.

The ends of the respective ribs 9 are seated in corresponding notches 11 of the step jacks, as shown in Figures 2 and 4, so as to maintain each unit 8 against longitudinal movement relative to the buttresses.

The tread portion of each unit 8 has the depending end lips 12 which are wedge shaped in

2

cross section and which fit into correspondingly shaped grooves 13 in the step jack 7 thus interlocking the tread and riser units 8 with the buttresses 5 thus holding said units in place and preventing the buttresses from spreading.

The grooves 13 of each buttress are directly opposite the grooves 13 of the other buttress and are arranged in stepped relation inwardly and upwardly, as shown more clearly in Figure 2.

10 The upper sides of the floor joist 2 are shoddered inwardly thus providing the upwardly facing shoulders 14 and 15 on which the corresponding ends of the floor slabs 3 rest. These slabs are also of precast concrete and the upper face 15 of the reduced portion of each joist 2 is formed with a longitudinal V-groove 16. The ends of the slabs have the transverse, depending, wedge shaped lips 17, the lips of the abutting ends of said slabs fitting into said V-grooves so as to interlock the floor slabs 3 with the joist.

20 The abutting margins of the floor slabs 3 are provided, one with a depending longitudinal rib 18 formed with an upwardly facing longitudinal V-groove 19 and the other with a longitudinal 25 depending lip 20 which is wedge shaped in cross section and which fits into said groove 19. The floor slabs 3 are thus locked against lateral or longitudinal displacement.

The outer tier of the floor slabs 3 are provided, 30 at their outer margins, with the depending longitudinal ribs 21 for strength.

The drawings and description are illustrative merely while the broad principle of the invention will be defined by the appended claim.

35 What I claim is:

A step construction comprising, spaced buttresses, the facing sides of the buttresses having step supports rising in stepped relation, said supports having alternately arranged notches and 40 longitudinal grooves, tread and riser units confined between the buttresses and having transverse end lips in said grooves and longitudinal, depending, ribs whose ends are seated in said notches, the forward margin of each tread having a longitudinal, depending riser whose lower 45 margin rests on the tread beneath.

LOUIS B. CLARK.
